SHEET FEEDING MACHINE

Alexander W. Nelson, Belleville, N. J.

Application November 18, 1937, Serial No. 175,253

28 Claims.

(Cl. 271—39)

This invention relates to an apparatus for feeding sheets such as may be used in photographically reproducing documents and it has for an object to automatically feed the documents to a predetermined position in the apparatus and to discharge the document after it has been photographed.

A further object of the invention is to provide a paper feeding mechanism which feeds the documents one at a time to the exposure position to be photographed or to a predetermined position; to provide a drive for the apparatus including a clutch which is controlled by the documents; to provide a combination of rotating discs and cam controlled fingers for moving the document into the exposure positions; to provide a paper guide with means therein preventing more than one document being delivered to the exposure position at a time, and another object of the invention is to provide means for taking up documents, one at a time, from a stack that is automatically fed to the delivery mechanism.

Other objects of the invention in relation to the paper feeding mechanism and the control of the apparatus will be more particularly understood from the following specification and the accompanying drawings, illustrating a preferred form of the invention, and in which:

Fig. 1 is a side elevation of the apparatus and the camera;

Fig. 2 is an elevation from the side opposite to Fig. 1;

Fig. 3 is a top plan view of the mechanism;

Fig. 4 is an elevation from the front end of the mechanism;

Fig. 5 is a longitudinal sectional view showing the operating mechanism and the mirrors;

Fig. 6 is a sectional detail of the clutch mechanism;

Fig. 7 is an elevation of the clutch mechanism with part of the cover broken away to show the release;

Fig. 8 shows the interior mechanism of one of the pick-up discs;

Fig. 9 is an elevation of Fig. 8 from the right side;

Fig. 10 is an edge view of Fig. 8 from the bottom;

Fig. 11 is a view of the opposite side of the take-up disc from Fig. 8;

Fig. 12 is a cross section of the cam for tilting the exposure table;

Fig. 13 is a section on line 13—13 of Fig. 12;

Fig. 14 is a hand operated release for the driving clutch.

Fig. 15 is a diagram of the take-up disc in the initial position of taking up the front sheet from a stack;

Fig. 16 is the second position of the take-up mechanism;

Fig. 17 shows a third position of the take-up mechanism;

Fig. 18 shows the take-up mechanism in the final position in which the document is delivered to the exposure table. Figs. 15, 16, 17 and 18 are 10 in diagram form and partially sectioned.

Fig. 19 shows one form of exposure table that may be used for the documents which is made from a wire frame, the wires of the frame being practically invisible in the photograph.

The present invention relates to sheet feeding mechanism that may be used for photographing legal and other documents up to the size that it is designed for, but the particular application in the drawings is shown in connection with photographing bank checks which occur as single sheets and in a variety of sizes and which are usually stacked together until they are to be photographically recorded. A stack of these checks is placed on their edge in a sliding drawer of the mechanism which is fed forward by a weight. A ledge is provided to engage the bottom edge of the front sheet and to take up the pressure of the weight which moves the drawer.

A pair of rotating discs are provided with friction pads which engage the front sheet of the stack and moves it on top of the ledge where it is released from the drawer pressure. In this position it is engaged by another pair of friction pads which move it forward into a paper guide 35 which is provided with a fixed friction pad located between the pair on the rotating disc to engage the opposite side of the document. This engagement holds back any additional sheets that may have been carried forward by the take-up mechanism and insures that only one sheet or check can be delivered to the exposure table for each operation. The further rotation of the discs bring a pair of gravity operated fingers into engagement with the edge of the document to continue its 40 movements after it is released by the friction pad and the document is finally engaged by a pair of cam controlled fingers which project it against a stop on the exposure table.

After the check is in place on the exposure 50 table with its front reflected on one mirror and its back on the other mirror the camera is operated to make an exposure and then the table with the check is deflected to permit the check to slide into a chute to complete the operation. 55

The exposure table is placed horizontally in line with the apex of the angularly positioned mirrors and the check is fed through this apex.

The apparatus is operated by a motor which, through reduction gears, operates a drive sprocket and this sprocket is connected by an over-running clutch of the ball type with the operating shaft of the mechanism. This clutch is released by a cam which engages the ball and is operated by a lever projecting from a rotating arbor so arranged that a hook placed in the path of this lever disconnects the clutch and stops the mechanism. This lever is operated by a plunger which is engaged by the stack of checks in the delivery drawer and so arranged that when the last check is removed from the drawer the plunger is released and the hook is brought into operation to declutch the mechanism. The declutching always takes place at the same position in the cycle of operation which completes the recording of the last check of the stack.

The present application is directed to the sheet feeding mechanism per se for any purpose.

In the drawings 11 is the base upon which the motion picture camera 12 is mounted and the mechanism embodied in the frame 14. The lights 15 are arranged to illuminate the exposure table 16 and the document thereon. This table is mounted on a shaft 17 and rests in the horizontal position by the arm 18 engaging the stop 19.

The mechanism is driven by the motor 20, through the belt 21, belt wheel 22, belt 23 and belt wheel 24 and chain 37, Fig. 2, engaging the sprocket wheel 38 loosely mounted on the sleeve 39 on the operating shaft 25, Fig. 6.

On the side indicated in Fig. 1, the shaft 25 is provided with a crank 26, connected to the pitman 27, pivoted at 28 in the bar 29, which slides vertically in the frame 14. The free end 30 of the pitman 27 engages the cam 31, mounted on the shaft 32 and controlling the fingers 33 which project the paper on the exposure table 16. The shaft 32 is biased by a weighted arm 34, Fig. 2 to move with a snap action and the rebound of the weight is absorbed by spring 36, engaging cam 35, mounted on shaft 32, Fig. 5.

The clutch mechanism is illustrated in Figs. 6 and 7 and comprises the freely running sprocket wheel 38 having a hub 40 in which the drum 41, keyed to the shaft 25 at 42, is located and an outer cover is provided at 43. The drum 41 is provided with one or more inclined apertures indicated at 47 and in which the ball, or roller, 46 is located and may be forced up the incline by a spring according to the common construction in over-running clutches of this type. The lever 48 is pivoted at 44 to the cover 43 and is formed on a cam at 45 which engages the roller 46 and if this lever is moved upwards from the position shown in Fig. 7, or if it is held stationary while the drum 41 revolves, the roller 46 is moved out of engagement with 40 and the operating shaft 25 is freed from the drive. The lever 48 rotates in the path of hook 49, mounted on shaft 50 and by lever 51 and weight 52 normally is held in the engaging position. The hook 49 is disengaged from 48 through rod 53 and plunger 54 so that as long as this plunger is moved to the right the clutch remains in engagement for the operation of the apparatus. When the plunger 54 is released, the weight 52 operates to disengage the clutch and stop the mechanism.

On the side of the mechanism, illustrated in Fig. 2, the cam 55, Figs. 12 and 13, is mounted on shaft 25 and is provided with an annular

groove 56 connecting with the rise 57 in which the pin 58, connected to lever 59, rides. Lever 59 is pivoted at 60 and through link 62 connects with lever 63, mounted on shaft 17 of the exposure table 16 and weighted at 64 to bring the table into the horizontal position as determined by the stop 19. A spring 61 may be provided, engaging lever 59 to absorb the rebound of the weight. By a bevel gear connection 65 on shaft 25, operating through rod 66 and bevel gear 67, the camera mechanism 12 is operated in synchronism with the delivery of the document on the exposure table.

The take-up mechanism for the documents comprises a pair of spaced friction pads, rotated with shaft 25. Each of the friction pads is located between a pair of discs as indicated in Figs. 8 to 11 inclusive. Fig. 8 shows the mechanism located between disc 71 and disc 71' which comprises an arm 72, pivoted at 73 and provided with a weight 74 at its outer end which rests against the stop 76 and is held against vibration by spring 75. The rubber pad 79 is mounted on the arm 77 which is arranged for radial movement on the disc by means of the 25 forked end which engages the collar on shaft 25 and the slot 78 which engages the pin 73. The arm 72 forms a yieldable support for the pad 79, controlled by weight 74. The centrifugal force acting on weight 74 is partially balanced by the 30 weight of pad 79 which is located further out from the centre 25 than weight 74. In practice the speed of rotation of disc 71 is relatively slow so that centrifugal force has comparatively little effect on the operation in which the weight 35 74, by gravity, forms the bias for the pad 79. Another pad 80, supported by the fixed support 81, is mounted on the disc in advance of pad 79, the pad 79 projects somewhat further than the pad 80. A weighted finger 82 is pivoted at 83 and 40 moves between the stops 84 and 84' on the disc 71'. This finger has a point 85 projecting beyond the disc to engage the edge of the document as the disc rotates.

A paper guide 88 is arranged to receive the 45 document as it is taken up from the stack. This guide includes a passage c between 88 and the cover member 87. Mounted on the paper guide 88, Fig. 5, is the arm 89 pivoted at 90 to 88 and carrying the friction pad 92 in the path of the 50 paper c extending from the pivot in the direction in which the paper moves. Tension is provided for arm 89 by spring 91. This pad is located between the pair of discs 71 carrying the take-up pads 79, 80.

The stack of sheets to be photographed are placed in drawer or receptacle 96 and rest with their edge on the bottom 97 as indicated at 98. This drawer is moved forward by the band 100, passing over the roller 101 to engage the weight 60 102, moving in the guide 103. This moves the stack forward as the sheets are used up. A thrust bar 99, attached to the cover 87, is provided parallel with the bottom 97 of the drawer and receives the pressure of the sheets as the drawer 65 moves forward. When several sheets move upward at a time, they are carried forward under the paper guide 88 as indicated in Fig. 15 where the pad 80 takes up the front sheet e and one or two other sheets on the back thereof. When 70 the pad 80 fixed on disc 71 moves into the releasing position, the yieldable pad 79 becomes effective to engage the outer sheet and to move it under the pad 92 fixedly supported by the paper guide 88 as indicated in Fig. 16. Pad 92 being 75

fixed prevents the movement of all of the sheets except the front one engaging pad 79 and these sheets fall back, as indicated at f to rest freely upon the thrust bar 99 until the next operation again takes up the front sheet of the stack. It will be noted that the fixed pad 80 of the movable member 71 gives the initial movement to the front sheet of the stack and releases it from the thrust bar 99. The yieldable pad 79 engages the sheet when it is released from 99. This yieldable pad projects further from 71 than pad 80 and carries the released sheets after it is partially released from the stack into the paper guide c. In the position shown in Fig. 17, the document e is disengaged from the pad 79 and at this stage the finger 85 is released from the cover 87 by the slot beginning at 93 enabling this finger to assume the position shown in Fig. 18 and at this stage the cam 31 is released from 30 and the fingers, 33, 33', moving in suitable slots in the cover, indicated at 106, gives the edge of the document e the final thrust to project it on table 16 against the fixed stop 94 which is the exposure position. In Fig. 13 the cam 51 is operated to deflect the exposure table 16 and discharge the document d by gravity into the chute 95 during the initial operation of taking up the next document e. The camera is operated between the positions indicated in Fig. 18 and Fig. 15 in the rotation of shaft 25.

It will be observed from Fig. 5 that the plunger 54, controlling the clutch, aligns with the aperture 54a of the drawer 96 so that as long as any checks remain in this drawer the plunger is prevented from entering this aperture and the mechanism continues to operate. On the other hand, when the last check is taken up the plunger enters the aperture 54a and the drive is de-clutched from the operating shaft 25. The clutch 40 may also be operated manually by the knob 111, operating rod 112, to rotate the inclined plane 114 to engage the member 113 depending from shaft 50 and to rotate this shaft to bring the hook 49 into the releasing position.

45 It has been common practice in machines of this type, designed to photograph both sides of a document by angularly disposed mirrors, to place the document on a glass exposure table. In practice when this is done the reflected light value for the side of a document resting on the table is reduced and one side of the photograph is more distinct than the other side. This condition can be avoided by the use of the wire frame table indicated in Fig. 19 in which the frame 121 is suitably connected to shaft 17 and is provided with a number of fine cross wires to support the document, indicated at 122. These wires are practically invisible in the photograph and they leave a smooth edge at the outer side of the frame over which the document readily slides when the frame is tilted.

The mechanism is biased in most cases by weights in preference to the use of springs and springs are used to take up the recoil to insure a smooth, positive operating action.

The principles of the invention admit of a variety of applications either in the combination shown or with other combinations without departing from the spirit and intent thereof.

70 Having thus described my invention, I claim:

1. In an apparatus for photographically reproducing documents in sheet form, a mechanism including in combination a drawer in which the sheets are stacked on their edge, means for moving the drawer and sheets forward, a fixed bar

having a flat face engaging the face of the outer sheet at its lower end and to take up the pressure of the drawer, a pad for releasing the outer sheet from said fixed bar, an exposure table for the document said pad moving the released sheet by friction forward to the exposure table. 5

2. In an apparatus for photographically reproducing documents in sheet form, a mechanism including in combination a drawer in which the sheets are stacked on their edge, means for moving the drawer and sheets forward, a fixed horizontal bar close to the bottom of the drawer and engaging the face of the outer sheet for receiving the pressure on said sheets, a pad for releasing the outer sheets from the stack to rest upon said bar, an exposure table for the document, said pad moving the released sheet towards the exposure table and means for holding back a following sheet. 10

3. In an apparatus for photographically reproducing documents in sheet form, a mechanism including in combination a drawer in which the sheets are stacked on their edge, means for moving the drawer and sheets forward, a fixed horizontal bar close to the bottom of the drawer 15 for receiving the pressure on said sheets, a paper guide, a rotating disc having a pad fixed thereon releasing the outer sheet from the stack to rest upon said bar, a movably mounted pad on said disc engaging the sheet after it is released and 20 delivering it to said paper guide, an exposure table, and means for moving the sheet onto said exposure table. 25

4. In an apparatus for photographically reproducing documents in sheet form, a mechanism 35 having an exposure table comprising a drawer in which the sheets are stacked on their edge, means for moving the drawer and sheets forward, a paper guide having a first friction pad thereon, a rotating disc having a second friction pad 40 engaging the outer sheet of the stack and moving said sheet through the paper guide and under said first friction pad, an exposure table for said sheet and means engaging the sheet after it is released by the second pad and moving it onto 45 said table.

5. In an apparatus for photographically reproducing documents in sheet form, a mechanism having an exposure table comprising a drawer in which the sheets are stacked on their edge, 50 means for moving the drawer and sheets forward, a paper guide, an arm pivoted on said guide and having its free end extending back from the mouth of the guide and a first friction pad thereon, a rotating disc having a second friction pad 55 engaging the outer sheet of the stack and moving it into said paper guide and under said first friction pad for moving the sheet toward the exposure table.

6. In an apparatus for photographically reproducing documents in sheet form, a mechanism comprising a drawer in which the sheets are stacked on their edge, means for moving the drawer and sheets forward, a paper guide, an exposure table connected with said guide, a rotating disc, a radially mounted arm having a pad thereon on said disc, biased means projecting said arm to bring the pad into position to engage the front sheet of the stack and deliver it to said guide and further means for delivering the sheet 70 to the exposure table.

7. In an apparatus for photographically reproducing documents in sheet form, a mechanism comprising a drawer in which the sheets are stacked on their edge, means for moving the 75

drawer and sheets forward, a paper guide, an exposure table connected with said guide, a rotat-
5 ing disc having a friction pad thereon engaging the front sheet of the stack and delivering it to the paper guide, a pair of fingers on said disc released by said mechanism to engage the sheet and move it forward and a pair of fingers released by a cam engaging the sheet after the engagement by the fingers on the disc for moving 10 the sheet to its final position.

8. In a check photographing machine, a mechanism including means for moving forward a stack of checks as they are used, a rotating disc for taking off the front sheet of the stack, a pair 15 of fingers operated by said disc engaging the paper sheet, a second pair of fingers operated by the mechanism engaging the sheet, a horizontally pivoted exposure table, a cam releasing said second pair of fingers to project the sheet upon said 20 table and means for tilting said table after the exposure to discharge the document.

9. In a check photographing machine, a mechanism, including means for moving forward a stack of checks as they are used, a rotating disc 25 for taking off the front sheet of the stack, a paper guide, means in said guide for preventing more than one sheet feeding forward at a time, a horizontally pivoted exposure table, fingers operated by said mechanism engaging the paper sheet and 30 moving it onto said exposure table and means for tilting said table after the exposure.

10. In a check photographing machine, a mechanism including a sliding drawer with a stack of checks placed on their edge, a weight for 35 forcing said drawer forward to deliver the checks, a fixed bar engaging the checks to take the thrust of the weight, a drive shaft, an operating shaft, a clutch connecting said shafts, a disc on said operating shaft having a friction pad engaging the front sheet of said stack to release it from said bar, an exposure table and means cooperating with said disc preventing more than one sheet feeding at a time, and moving the sheet onto the exposure table.

11. In a check photographing machine, a mechanism including a sliding drawer with a stack of checks placed on their edge, a weight for forcing said drawer forward to deliver the checks, a fixed bar engaging the checks to take 50 the thrust of the weight, a rotating drive shaft, an operating shaft, a clutch connecting said shafts, a disc on said operating shaft having a friction pad engaging the front sheet of said stack to release it from said bar and a rod normally engaging the outer sheet of the stack for disconnecting said clutch when the stack of 55 checks in the drawer is exhausted.

12. A paper feeding machine for feeding single paper sheets individually from a stack comprising a holder for moving forward the stacks as the sheets are used, a paper guide, a rotating friction pad engaging the outer sheet and delivering it to said guide, a fixed pad controlled by a spring on said guide, said sheet passing between the moving pad and the fixed pad to prevent more than one sheet entering the guide and means for delivering the sheet.

13. A sheet feeding machine for feeding paper sheets from a stack, comprising a receptacle in 70 which said sheets are stacked, means for moving said stack forward, means for taking up the front sheet from said stack comprising a moving member having a pad rigidly mounted thereon, and a second pad on said moving member, movable by a bias with respect to said member said pads

engaging the sheet and moving it forward in the feeding operation.

14. A sheet feeding machine for feeding paper from a stack, comprising a receptacle in which the sheets are stacked, means for moving said stack forward, means for taking up the front sheet from the stack including a moving member having a pad rigidly mounted thereon engaging the sheet and giving it an initial movement, a second pad projected from said moving member 10 engaging the sheet and feeding it forward from the stock and means for projecting said second pad to engage the sheet.

15. A sheet feeding machine for feeding paper sheets from a stack, comprising a receptacle in 15 which the sheets are stacked, means for moving the stack forward, means for taking up the front sheet from the stack including a rotating member having a pad fixed thereon engaging the front sheet for giving it an initial movement, a second pad radially mounted on said rotating member 20 and projected to engage the sheet for feeding it forward from the stock.

16. A sheet feeding machine for feeding paper sheets from a stack, comprising a receptacle in 25 which the sheets are stacked, means for moving the stack forward, a fixed paper guide having a pad mounted thereon, means for taking up the front sheet from the stack including a moving member having a pad thereon engaging the front 30 sheet and moving it into said paper guide and the pad on said guide engaging the back of said sheet to prevent more than one sheet feeding at a time.

17. A sheet feeding machine for feeding paper 35 sheets from a stack, comprising a receptacle in which the sheets are stacked, means for moving said stack forward, a fixed paper guide, a spring mounted pad on said guide, a moving member having a pad thereon engaging the front sheet 40 of the stack and moving it into said paper guide and the pad on said guide engaging the back of the sheet to prevent more than one sheet feeding at a time.

18. A sheet feeding machine for feeding paper 45 sheets from a stack, comprising a receptacle in which the sheets are stacked, means for moving said stack forward, a paper guide having a pad mounted thereon, means for taking up the front sheet from said stack including a moving member having a first pad rigidly mounted thereon and a second pad yieldably mounted thereon, said first pad engaging the front sheet of the stock to give it an initial movement towards said guide, said second pad carrying said sheet into said 50 guide and the pad on said guide engaging the back of the sheet as it moves into said guide.

19. A sheet feeding machine for feeding paper sheets from a stack, comprising a receptacle in 55 which the sheets are stacked, means for moving said stack forward, a paper guide having a pad mounted thereon, a rotating member having a pad thereon engaging the front sheet of the stack and carrying said sheet into said guide, the pad on said guide engaging the back of said sheet to prevent the movement of more than one sheet at a time, and fingers pivoted on said rotating member and weighted to project from said member as it rotates, to engage said sheet and move it forward in the feeding operation.

20. A sheet feeding machine for feeding paper sheets from a stack, comprising a receptacle in 60 which the sheets are stacked, means for moving said stack forward, a fixed bar engaging the front 65 sheet of the stack near the lower end to take the thrust of the stack.

5 of the moving stack, a movable member with a first pad fixed thereon engaging the front sheet of the stock and releasing it from said bar and a second pad on said movable member engaging the front sheet that has been released and moving it forward in the feeding operation.

10 21. A sheet feeding machine for feeding paper sheets from a stack, comprising a receptacle for the paper stack having a back supporting the stack, means for moving said receptacle forward, a drive shaft, a moving member connected with said drive shaft by a clutch, a weighted arm controlling said clutch, a rod pivoted to said arm and engaging the front sheet of the stack and a pad on said moving member engaging the front sheet of the stack and feeding it forward, said supporting back having an aperture registering with the end of said rod, said rod operating said weighted arm to disengage said clutch when it enters said aperture and said rod being prevented from entering said aperture by the sheets until the last sheet of the stack is removed.

15 22. A sheet feeding machine for feeding paper sheets from a stack, comprising a receptacle for the paper stack, means for moving the stack forward, a paper guide with a pad thereon, a moving member having a pair of pads thereon spaced one on each side of the pad on said guide and arranged to engage the front sheet of the stack and feed it forward to said guide, the pad on said guide being arranged to engage the back of the sheet.

20 23. A sheet feeding machine for feeding paper sheets from a stack, comprising a receptacle in which the sheets are stacked, means for moving the stack forward, a rotating member, an arm mounted for radial movement on said member, a weighted arm pivoted on said rotating member and engaging said arm to project said arm radially and a pad on said arm engaging the front sheet of said stack to feed the sheet.

25 24. A sheet feeding machine for feeding paper sheets from a stack, comprising a receptacle in which the sheets are stacked, means for moving said stack forward, a drive shaft, a rotating member driven by said shaft, a yieldable arm mounted on said member engaging the front sheet of said

stack to feed it forward, a paper guide for receiving said sheet, a pair of fingers engaging the sheet after it enters said guide and a cam operated by said drive shaft for operating said fingers to project the sheet forward.

5

26 25. A sheet feeding machine for feeding paper sheets from a stack, comprising a receptacle for the paper stack, means for moving the stack forward, a paper guide, a moving member having a pad thereon engaging the front sheet of the stack, and delivering this sheet to said paper guide, a cover member for said moving member and a biased finger pivoted on said moving member and held in an inactive position by said cover member and when released engaging said sheet to move it forward in said paper guide.

20 26. A sheet feeding machine for feeding paper sheets from a stack, comprising a receptacle for the paper stack, means for moving the stack forward, a paper guide, a rotating member having a pad thereon engaging the front sheet of the stack and delivering this sheet to said paper guide, a cover member for said rotating member and a biased finger pivoted on said rotating member and released by said cover member to engage the 25 paper sheet after it is delivered to said paper guide to move said sheet forward.

25 27. A sheet feeding machine for feeding paper sheets from a stack, comprising a frame, a receptacle for the paper stack, means for moving the stack forward, a paper guide supported by said frame, a rotating member having a pad thereon engaging the front sheet of the stack and delivering this sheet to said paper guide, a finger pivoted to said rotating member and engaging 30 said sheet for part of the rotation of said member to move the sheet forward, a second finger pivoted in said frame and a cam operated with said rotating member to release said second finger to engage the sheet and move it forward in said guide.

30 28. A sheet feeding machine for feeding paper sheets from a stack, as in claim 27, the engagement of said fingers with the paper sheet being arranged to overlap each other so that one set of fingers succeeds the other in impelling the sheet forward.

ALEXANDER W. NELSON.
